UNITED STATES PATENT OFFICE.

THURBER J. GILLETTE, OF SYRACUSE, NEW YORK, ASSIGNOR OF TWO-THIRDS TO DAVID D. GREGORY, OF SAME PLACE.

GAGE FOR SQUARES.

SPECIFICATION forming part of Letters Patent No. 373,929, dated November 29, 1887.

Application filed March 22, 1887. Serial No. 231,890. (No model.)

To all whom it may concern:

Be it known that I, THURBER J. GILLETTE, of Syracuse, county of Onondaga, and State of New York, have invented an Improvement in 5 Gages for Squares, of which the following description, in connection with the accompanying drawings, is a specification, like letters on the drawings representing like parts.

This invention has for its object to provide 10 a square with gages particularly adapted to be used by carpenters to accurately measure miters in stair stringers, it being also adapted for measuring rafters to be used in building, as in the roof of a building, and whereby each 15 rafter may be cut at exactly the same bevel or angle of inclination, so that when the said rafters are erected into position to form the frame of the roof the ends of opposite rafters will be matched and the ridge or comb of the 20 roof will be made to fall at the center of the building and be substantially perfectly straight.

In the manufacture of stringers for stairs as heretofore practiced and known to me the 25 miters have been marked out by applying the square to the board to form the stringer. The workman in marking the stringers is guided solely by his eye, and when working rapidly it frequently happens that the square 30 is not in every case applied to the board or timber accurately—as, for instance, when it is desired the miter should be twelve inches long on one side and ten inches on the other, the workman applying the square to the board or 35 timber hurriedly marks twelve and one-eighth inches on one side and nine and seven-eighths inches on the other, and at the next application of the square to the board marks eleven and seven-eighths on one side and ten and one- 40 eighth on the other. It will thus be seen that the stringers when placed in position to form the sides of the stairs are not matched, so that when the boards are nailed thereto the steps thus formed are uneven and irregular in size 45 and shape. Also, in the marking of timbers to form rafters, especially for buildings having pitched roofs, the same error occurs, and as a result some of the rafters are given a bevel differing from other rafters or are made longer, 50 which will, it is obvious, result in not only throwing the ridge of the roof out of the cen-

ter of the building, but also giving a crooked line to the ridge.

It is the object of this invention to overcome the difficulty referred to and to enable a carpenter to mark stringers, rafters, &c., with the greatest rapidity and utmost accuracy. 55

My invention therefore consists, essentially, of a gage composed of a body portion slotted to fit one arm of a measuring square, the said body portion being provided with arms having a vertical shoulder or shoulders at right angles to the face of the said square, the said gage preferably having two shoulders, in order that it may be used either side up. 65

Figure 1 shows a carpenter's steel square with my improved miter-gage applied thereto. Fig. 2 is a view of the gage removed, looking at it in the direction of the arrow 2; Fig. 3, a view of the gage, looking at it in the direction 70 of the arrow 3; and Fig. 4 is a detail to be referred to.

The square A is and may be of any usual construction, it being provided with usual graduations, herein shown as feet and fractions of a foot. Each arm a' a'' of the square A has fitted upon it a miter-gage, B, which consists, as shown in Fig. 2, of a slotted body portion, a^3 , having arms a^4 , provided with shoulders a^5 . Each arm a' a'' of the square enters the 80 slot 2 of the body a^3 , and the gage is secured to the arm of the square on which it is placed by a set-screw, b' , which acts against an adjusting-block, b , which is fitted into the said slot 2 and bears against the edge of the square, 85 the block b having claws b^3 (see Fig. 4) to engage the sides of the body a^3 in its normal position. (Shown in Figs. 1 and 2.) The edge or side 3 of the bar b next the edge of the square is smooth. 90

The gages may be applied to the arms of the square and be adjusted thereon so that the faces of the shoulders a^5 will register with any desired distance mark thereon and form a gage or stop. 95

In marking miters for stringers to be employed in building stairs, the gages will be set on the arms a' a'' at the desired division on the scale, the gage on the arm a' being shown as set at twelve inches and the gage on the arm a'' being set at eight inches, the zero being the apex of the arms. With the gages set as shown, 100

the workman applies the square to the stringers, the lower shoulder, a^5 , of each gage resting against the edge of the stringer, while the square between the gages rests upon the face 5 or side of the stringer, and when in this position the workman marks out the miter. With one miter marked out, the square is run along the edge of the board until the lower shoulder, a^5 , of the rearmost gage arrives in the position just vacated by the foremost gage, a second miter being then marked out. This is continued until the desired number of miters has been marked. It will be seen that the possibility of error in marking is reduced to a minimum, while at the same time the marking may be done very rapidly.

When it is desired to mark timbers for rafters for buildings having a pitched roof and insure true central position for the ridge or 20 comb of the roof, the gages will be set on the square, their position being adjusted according to the width of the building and the pitch desired for the roof. Suppose a building is to be twenty-four feet wide and the pitch of 25 the roof is to be eight inches to the foot. To do this the gage on the long arm a' will be set at twelve inches, as shown, while the gage on the arm a^2 will be set at eight inches. With the gages in position, the square is first applied 30 to the timber or board to form the rafters, as in the marking of miters, above described, and the bevel for the foot of the rafters is formed by marking on the board from the apex to the shoulder a^5 of the gage on the long arm a' , the board being also marked at the other gage to 35 form the starting-point from which to measure again.

The proper length of rafters for the roof is obtained by applying the square to the timber 40 or board twelve times, measuring each time from gage to gage, and on the last movement the bevel or inclination for the upper end of the rafter is obtained by marking on the board from the gage on the arm a' to the apex of the 45 square. In this way it will thus be seen that the rafters are all of the same bevel and length, so that the bevel sides of co-operating or op-

posite rafters correspond and come together at exactly the center of the roof, and consequently the ridge of the roof is kept substantially perfectly straight.

By means of the arm a' and shoulder a^5 the square may be applied to the board to be measured with rapidity and accuracy, the said arm and shoulder forming a bearing to 55 rest against the board, thus obviating all danger of slipping of the square, which might occur if the said arm and shoulder were not used; and, furthermore, the edge of the square meets the edge of the board at the point where the shoulder a^5 meets the board, so that all calculations in adjusting the gage on the square are dispensed with.

It is evident that the shoulder a^5 on the arm below the arm of the square may be dispensed 65 with, and the arm itself form a bearing surface to rest against the edge of the board; but the two arms are preferable, so that the square can be used either side up.

I claim—
1. A miter-gage for steel squares, consisting of a body portion slotted to fit an arm of the square, and provided with an arm, a' , having a shoulder, a^5 , at right angles to the face of the said square, to operate substantially as 75 described.
2. A miter-gage for steel squares, consisting of a body portion slotted to fit an arm of the square, and provided with two arms, a' , having shoulders a^5 at right angles to the face 80 of the square, substantially as described.
3. The combination, with the arms of a steel square, of two miter-gages adjustably fitted thereon, and having shoulders a^5 at right angles to the face of the said arms, substantially 85 as described.

In testimony whereof I have signed my name to this specification in the presence of two subscribing witnesses.

THURBER J. GILLETTE.
